[57] CLAIM

The ornamental design for a receptacle connector, as shown and described.

DESCRIPTION

FIG. 1 is a perspective view of a receptacle connector showing a first embodiment of our new design;

FIG. 2 is a top plan view thereof;

FIG. 3 is a front elevational view thereof;

FIG. 4 is an elevational view of the right side of the connector illustrated in FIG. 1, the left side being a mirror image thereof;

FIG. 5 is rear elevational view thereof;

FIG. 6 is a bottom plan view thereof;

FIG. 7 is a perspective view of a receptacle connector showing a second embodiment of our new design;

FIG. 8 is a top plan view thereof, with the bottom being a mirror image thereof;

FIG. 9 is an elevational view of the right side of the connector illustrated in FIG. 7, with the left side being a mirror image thereof;

FIG. 10 is a front elevational view thereof; and,

FIG. 11 is a rear elevational view thereof.
